GRENADE MAGAZINE ATTACHMENT FOR
SERVICE RIFLES

John H. Pearson, Lowell, Mass.

Application July 21, 1942, Serial No. 451,784

5 Claims. (Cl. 42—1)

This invention is an attachment for service weapons of small calibre, for feeding a plurality of projectiles into a guide to be propelled by pressure of explosion gases on a rifle barrel rod carried by the projectile.

The weapons of the foot soldier in the United States Army are tending to be magazine fed and automatically loaded by means of gas pressure or recoil operation, the mechanism usually including an operating rod or bolt handle, which reciprocates with each shot. The great need of the soldier, however, is an individual weapon, easily transported and decisive in effect, which can be used in comparatively close-in defense against armored vehicles, particularly tanks. A large calibre weapon, firing armor-piercing ammunition, is effective against such vehicles, but is costly to manufacture, and the supply is necessarily limited. Among the expedients used to build up the morale of foot soldiers not equipped with such weapons has been the use of a quart bottle of gasoline and oil, fitted with a lighter wrapped in cotton waste, and thrown from the hand against the sides or top of armor clad vehicles. The glass bottle breaks against the metal, the contents spread over the target, and the tank crew are made insufferably hot and must subject themselves to fire in dismounting from the vehicle.

It has been found by experiment that a man must usually expose himself to throw such a "Molotov cocktail," as they have been termed, that at least a quart of liquid is needed to be effective, and that the limit of range is about thirty yards. The danger of premature explosion or conflagration is constantly present, one hit will rarely disable a tank, and cotton waste, glass bottles, and lighters are difficult to find on a battlefield.

The object of this invention is to provide a frangible grenade, to be usable, either as a hand missile or as a projectile from an automatic weapon, capable of being aimed and propelled against an armored vehicle at greater than throwing range.

Another object of this invention is to provide a magazine fed weapon for projecting grenades, enabling a soldier to have more than one opportunity to hit his target, and when once successful, permitting him to build up a fire by directing his aim at other parts of the vehicle.

A further object is to provide an attachment to the ordinary service weapon, which does not prevent its ordinary use, but which acts as a guide for a plurality of grenades propelled by the explosion of blank cartridges within the weapon, and reloaded by the movement of the bolt handle or operating rod handle of the weapon after each shot.

One of the greatest advantages of this device

is that a soldier who is in a fox hole or slit trench which protects his entire body up to the arms and head, the head being protected by a helmet, can fire not only one grenade but a number of them successively without shifting his left arm which carries the principal weight of the rifle and in fact without shifting either arm for reloading.

It includes a light grenade guide attached to a shoulder rifle with a magazine which, when attached thereto, can often rest on the ground so as to steady the piece and to keep it properly sighted. The soldier, without exposing much of himself, can get set with the magazine resting on the ground and the rifle stock supported against his right shoulder and resting on his right and left elbows so that he can continue firing without changing the sight of the rifle or reaching out to the muzzle to reload.

A still further object of this invention is to provide a bomb or grenade guide which is readily attached to common service weapons, and which is easily transportable, because it eliminates the use of an additional barrel of large calibre to withstand explosion gas pressure.

Throughout the following description and in the claims, the words "projectile" and "grenade" are synonymous, and each, as used, is intended to convey the idea of a bomb, a pyrotechnic, missile, or a grenade projected from a weapon.

In the drawings

Fig. 1 is a side elevation of a Garand rifle with my magazine attached and in normal operative or firing position.

Fig. 2 is a plan view of Fig. 1.

Fig. 3 is a side elevation, partly in section, of the muzzle end of a service rifle of the Garand type with my loaded magazine in position before a projectile is loaded into the guide.

Fig. 4 is a section of Fig. 3 on the line 4—4 and Fig. 5 is a section of Fig. 3 on the line 5—5.

Fig. 6 is a diagram showing a soldier in a trench using my device with a service rifle.

Fig. 7 is a longitudinal section of a projectile with the rifle rod extended.

Fig. 8 is a section on line 8—8 of Fig. 7 looking in the direction of the arrow.

Fig. 8A is an enlarged detail showing the ball and socket lock of the rifle rod.

Fig. 9 is an enlarged sectional elevation on line 9—9 and Fig. 10 is an enlarged sectional elevation on line 10—10 of Fig. 7.

Fig. 11 is a side elevation of a modified form of projectile guide and its attachments showing also part of the magazine and with the closure projecting from the guide.

Fig. 12 is a sectional elevation similar to Fig. 3 of the modification shown in Fig. 11.

Fig. 13 is an elevation as from the right of Fig. 11 but with the closure retracted.

Fig. 14 is a view from the bottom of the device

shown in Fig. 11, 12 and 13 with the closure retracted.

Fig. 15 is a detail, partly in section, showing the double sheave pulley.

Fig. 16 is a detail showing the closure retracting spring assembly partly in section, and Figs. 17, 18, 19, are details of modifications.

Fig. 6 of the drawings shows a shoulder rifle such as A with my magazine C attached held by the soldier S with the butt 1 against his right shoulder 2 and with the rifle supported mainly by his left arm 3 but with his right arm, which is not shown also supporting the piece in such a way that the trigger finger of the right hand can pull the trigger without moving the rifle.

In the drawings, A is a United States rifle, calibre 30, M1, and is the rifle with which the infantry soldier of the United States Army is now equipped. It is fed from a clip of eight cartridges and its loading is accomplished by gas from the discharge of a cartridge, passing from the barrel 12, through a gas port 13, and striking a piston rod 14, which motivates the extracting, loading, and cocking mechanism. 15 is the operating rod handle, attached to piston rod or operating rod 14, and by which the rifle can be hand loaded, or the chamber opened for inspection. Handle 15 slides to the rear with each discharge, approximately four inches, or about one inch further than the length of a cartridge, and it is returned to position by a strong spring within the rifle. 11 is a bayonet stud, upon which the service bayonet may be fastened and 16 is the front sight of the weapon, which, as shown in Fig. 1, is not obstructed by my invention.

My device consists of a tubular guide B, the upper half of which is semi-circular in cross section, as shown at 21, and the lower half of which is shaped, as shown at 22, to receive and guide a sliding closure 23, the upper surface of which, at 24, is semi-circular, and forms a complete circle with the inside face of 21.

The end 25 of the guide B is closed and is rigidly connected with a carrying and attaching handle H. Extending upward is a neck 26 through which is a hole 27 which fits snugly over the muzzle of the barrel 12 of rifle A. Extending downward from handle H is an arm 30, from which at right angles extend the hands 31 and 32, each of which is bent ninety degrees and extend forward at 33 and 34 serving as a guide and to steady the magazine C when that is in place. At each forward end are the upwardly extending fingers 35 and 36.

The metal 28 of handle H is formed with a slot 4 of a well known type which fits over the bayonet stud 11 and is locked in place by catch 29 of a well known type having a thumb button 5 at one end and tooth 6 at the other end.

The closure 23, has oppositely extending ears 37 and 38, which project through and travel along parallel slots 40 and 41, in the part 21 of guide B. Ear 37 also extends into a slot 42 in the long arm 43 of a bell crank lever E which is pivoted at 44 to finger 35 and has its short arm 45 connected at its end by a flexible connection F to operating rod handle 15.

The lower portion of guide B, below the shaped portion 22, extends downwardly to form parallel sides 46, 46, the rear portion being formed by arm 30 and the forward portion 47 being parallel thereto but containing a button 48, operating in a recess 49, in 47, whereby the magazine C can be released or locked in position.

Guide B need be of only light construction,

because no explosion takes place therein, due to exhaust vents 50, through which the exploded gas escapes.

Magazine C may also be of light construction and consists of sides 51 and 52, bottom 53, ends 54 and 55, and open top 56. End 54 fits snugly against arm 30, is steadied by hands 33 and 34 and has a projection 51, which enters a corresponding recess 58, in arm 30, as part of a removable connection. End 55, at or near its top, has an outwardly projecting spring catch 87, which enters a recess 49 in end portion 47 of guide B and which can be forced therefrom by pressure on button 48 to detach magazine C. A grenade follower plate 59, having two parallel and downwardly projecting guide pins, such as 60, is under constant pressure by springs such as 61, guided by pins such as 62, attached to bottom 53. Sides 51 and 52 converge at 63 and 64 and form a neck 65, of sufficient width to admit one projectile D, at a time. A spring catch 66, as shown in dotted lines in Fig. 5, holds projectiles D, in the magazine C before it is attached to or is inserted in guide B. Upon insertion, as shown in Fig. 5, the sides 46, 46, of B force catch 66 to bend out of the way and allow the topmost projectile to be free to press against the bottom 67 of closure 23 which forms part of guide B but is slidable therein and opens and closes the mouth or open top 56 of magazine C.

Ear 38 of closure 23 is slidable in slot 41 and spring 68, attached to it and to B at 69, returns the closure 23 to a closed position after it has been opened by bell crank lever E to admit a new projectile D by a pull on flexible connection F.

The front of projectile D is a tubular container 70 with its forward end 71 rounded and its rear edge offset and threadedly connected to a metal end cap 72 of, fire and chemical resistant material. All of container 70 or only end 71 may be made of glass or other frangible material, such as a plastic composition, and it may be opaque, translucent, or transparent. As shown in Fig. 7, D is of transparent glass and is filled with an inflammable liquid I, such as a combination of gasoline and oil. Air may be exhausted therefrom and the container only partially filled in order to assist in breaking of the material and spreading of its contents. End cap 72 is formed with an inwardly projecting circular thimble with a recess 73, and an inwardly projecting neck 74, to which a frangible tube 75 is threadedly connected at 76. Slidable in tube 75 is a rifle barrel rod 77 of a diameter to make a close fit with the bore of the service rifle, and normally projecting from the interior 78 of tube 75 by reason of pressure from a spring 79. Figs. 7, 8, and 8A.

In its extended position, rod 77 is held extended and prevented from revolving by balls 80, 80, each ball being seated in one of a series of radial sockets 8, 8, in the exterior surface of rod 77. Balls 80, 80, are slidable and captive in tracks 82, 82, in a disc filler 83, permanently fastened to end cap 72, a spring 84, maintaining constant pressure on each of said balls. When loaded into magazine C, the rod 77 of each projectile D, is compressed into its tube 75, but when a projectile D reaches a central position in projectile guide B, its spring 79 forces the rod 77, into the muzzle and barrel 12 of the rifle A and considerably beyond gas port 13 in which position it is held by balls 80, 80, which serve as a catch or lock.

As shown in Fig. 10, each rod 77 is tubular as at 181 throughout the greater part of its length

and is pierced by a plurality of radial slots or passages shown at 182, 182. The hole of tube 181 is filled with slow burning powder, shown at 183, which also fills the slots 182, 182. Only a small portion, at the extremity of rod 77, is empty or unfilled as shown at 184.

This device is removable from the rifle in as simple a movement as removing a bayonet and in the same way by pressing the button 5 of catch 29 of handle H. The projectile guide B and flexible connection F may be carried on the rifle for long distances as they are comparatively light, do not interfere with firing or aiming, and have advantages as a flash hider and as an upward recoil compensator. The magazine C, being removable, and being the heavy portion of the device, can be carried in accompanying weapon carriers, slung from the issue cartridge belt, or hung from the shoulders by a carrying strap. It is also to be noted that upon removal of the magazine C, the hands 33, 34 form a convenient gun rest, similar to the bipod of the Browning automatic rifle, cal. .30, with the exception that they are not shown as adjustable for height.

Upon sighting the approach of an armor clad target, the soldier, who has been carrying projectile guide B attached to his rifle in place of his bayonet, inserts a loaded magazine C, into the opening formed by sides 46, 46, and ends 30, 47. It is locked in place by means of projections 57 and 87, and the topmost projectile D is released, ready to be forced into guide B, since spring catch 66 is pushed out of contact with the topmost projectile D, by sides 46, 46.

Operating rod handle 15, with flexible connection F attached, is pulled to the rear and a clip of eight blank cartridges is inserted in the rifle magazine. By this same operation, through flexible connection F and bell crank lever E, the closure 23 is projected out of projectile guide B, as shown in dotted lines in Figs. 1 and 2. As closure 23 travels outward, spring 61, together with projectile follower plate 59, pushes a projectile D into projectile guide B. The return spring of the rifle then returns the operating rod handle 15 of the rifle to its closed position, and this in turn releases F and E and allows spring 68 to return closure 23 to its closed position.

At the moment when projectile D is properly centered in projectile guide B, and end 89 passes in front of the muzzle of barrel 12, spring 79 projects rod 77 into the barrel of the rifle, past the gas port 13, effectively blocking it. Balls 80, 80, are then pressed by springs 84, 84, into sockets 8, 8, to hold 77 from returning or revolving separately from 70. If by mechanical fault, projectile D is not fed into guide B, a bullet fired by error is free to pass and a blank cartridge free to explode. If by mechanical fault, projectile D occupies projectile guide B but rod 77 fails to enter the barrel, a bullet, fired by error, will have room to expand in B and not damage the rifle, while in the firing of a blank cartridge the explosion will be dispersed through exhaust holes 59. Rod 77 is slightly tapered or chamfered at its end 89, so as to aid in entering the barrel of the rifle and in its extended position, it will penetrate beyond the gas port from four to eight inches into the barrel.

The rifle, preferably supported at the muzzle by the magazine C, may now be aimed through the usual sights or through a special rear sight not shown, the sight being raised sufficiently to compensate for the shorter trajectory of the com-

paratively heavy projectile D. A pull of the rifle trigger discharges the blank cartridge loaded into the rifle chamber by the return of the operating rod handle and the hot gases of explosion travel the length of the barrel. Upon reaching 77, they press against it with great force, and entering the unfilled central portion 184, tend to expand 77 sufficiently to make a tight fit, thereby aiding the lands and grooves of the barrel to give 77 and its projectile D a twisting movement. Point 89 pierces any wad of paper pushed ahead of the ignited gases, so that the heat of the explosion ignites the powder train 183.

Rod 77 and projectile D are thus forced out of barrel 12 and guide B respectively, with a twisting motion to keep the projectile in its intended path and with powder train 183 burning. As projectile D travels through the air, balls 80, 80 are forced outward radially, by centrifugal force, releasing 77 to slide forward by its inertia upon impact of the projectile with the target. Nearing the end of its trajectory, powder train 183, by prearranged timing, burns through to slots 182, 182, so that powder contained therein is exposed to the air and burns with intensity in a plurality of radial directions. Upon impact, frangible container 70 and frangible tube 75 are broken, the contents of 70 are spread over the target and rifle rod 77, with spring 79 no longer captive, is forced by inertia, through end cap 72 against the inflammable liquid I, igniting it.

Meantime, the passage of rod 77 has uncovered gas port 13, and the automatic mechanism of the rifle is permitted to reload it and the projectile 35 guide B from magazine C by the process described above.

It is to be understood that the form of my invention, herewith shown and described, is to be taken as a preferred example, and that various 40 changes in the shape, size, and arrangement of parts may be resorted to, without departing from the spirit of my invention, or the scope of the subjoined claims.

It is also obvious that the device can be used 45 with a recoil operated weapon having a moving bolt handle, such as a Browning machine gun, cal. 30, by simple changes in means of attachment to such weapon, not affecting the operation and easily accomplished by one familiar with the 50 trade.

Furthermore, it is obvious that the projectile D can be removed and an impact exploding, time 55 exploding fragmentation or gas grenade can be substituted therefor by adding to each an interiorly sliding rod to be spring inserted in the barrel.

It may also be used, with no changes in construction, on the model 1903 bolt operated rifle, by attaching the flexible connection F to the bolt 60 handle, but such use would be hand operated feed rather than the mechanical feed considered to be preferable.

In Figs. 11 to 16, I show a modification in which the tubular guide G has a horizontal slot 90 for 65 an ear 91 which projects from closure M, such closure being a complete tube or a cylinder instead of as shown at 23.

There is another slot 92, parallel with 90, which extends lengthwise on the other side of guide G 70 and through this projects another ear 93.

The means for moving closure M in and out of guide G are shown as pulleys such as P, P, which are fixed to a shaft 94 which extends through the downwardly extending part 7 of guide 75 G below closure M and in such a position that

they will not interfere with the magazine L when it is in place. Each pulley P has a large sheave 95 around which passes a flexible connection 97 attached respectively to ears 91 and 93.

Each pulley P also has a small sheave 96, and around one of these sheaves passes the flexible connection K which extends back to a bolt handle 15 or to one of any type. This connection K is attached to the bolt handle of a Garand, a Springfield or a Krag rifle so that when the bolt handle is moved back, either automatically or by hand, closure M is carried forward as shown in Fig. 11.

For retracting closure M to the position shown in Figs. 12 and 13, a convenient arrangement is a spring drum or sheave such as N or preferably two such sheaves, one on each side, each carried by a spring of the watch type 99 fixed to the guide G at 17 and having wound around it a flexible connection 100 attached to an ear 91 or 93. Preferably I use two such pulleys N, N, each with a connection to an ear 91 or 93 so that the pull will be even on both sides.

The forward pull is transmitted from one side to another by the shaft 94 so that closure M will not bind either when being moved out or being moved back into firing position.

The top of the magazine L fits inside of the downwardly extending part 7 of closure G which preferably is somewhat deeper than where the arm construction such as 30, 31 is used. There may be a hook 9 to hook over a cross rod 18 at the front, and at the back there can be a pull button 19 whereby the magazine can be hooked over at the front and the button 19 pushed in to a hole 29 so as to hold the magazine at the back.

Instead of the construction of the projectile shown in Figs. 7, 8, 8A, 9 and 10, in Figs. 17 and 18 I show a modification indicated by U. This has a casing 110 substantially similar to 70 with a base 111. There are no balls.

The tube 112 is substantially similar to 75 and has passages such as 113 through which flame from the slow burning powder 122 inside can pass through to the inflammable mixture 115 or what might be called the main filling. There is also at 116 a pocket or pockets of slow burning powder which may be of a type used in rockets and preferably in one or more of these pockets there is a spring catch 117 which ordinarily is held in the dotted line position shown in Fig. 18 by the outside of the tube 120 which corresponds with rod 77 except that its end 121 which enters the rifle barrel is not pointed but open so that when the cartridge in the rifle is exploded the slow burning train of powder 122 in tube 120 is ignited. A blank cartridge with an inflammable wad or with no wad at all can be used in place of the pointed end 89 of the construction shown in Fig. 7.

Through the walls of this tube are shown passages such as 123, which register with passages 113 when tube 120 is forced out by a spring such as 119. When they register, the spring catch such as 117 drops through the passage 113 into passage 123 and locks the tube 120 in position. These passages also serve to allow the slow burning powder 122 to ignite the powder 116.

If any of the powder in tube 120 gets out of place or if the catch 117 fails to work, it simply means that tube 120 would compress spring 119

and the powder 122 in the tube would ignite that in a pocket such as 116 or in another pocket adjoining another passage such as 113.

The catch 117 may be omitted entirely as shown in Fig. 17 and through a hole such as 131 in a tube such as 130, the end of a spring such as 132 can be passed, the other end 133 being locked in a similar way through the inside of the tube 134.

With these constructions the tube 112 in which the ignition tube 120 slides need not be made of frangible material but may be made of metal.

As shown in Fig. 19, the spring 117 can be cut out of the material of the outside tube 112 and the passages 113 and 123 may be wider and somewhat longer than the inwardly projecting tooth of spring 117 so that there will be plenty of room for the flame to pass from the inside of the tube 120 through the tube 112 into the body of the projectile U.

I claim:

1. In a rifle grenade, a container; an axial tube extending centrally through the container; a rifle barrel rod slidable in said axial tube; spring means to project the rifle barrel rod from the end of the axial tube; and means for locking the rod from returning into, or revolving apart from the container.

2. In an automatic, small calibre weapon having a barrel with a muzzle; a grenade guide in extension of the muzzle of the barrel and a grenade magazine for automatically feeding grenades to said guide; a grenade comprising a container, an axial tube extending centrally through the container in axial alignment with the barrel, a hollow rifle barrel rod slidable in the axial tube of the container, said rod being radially slotted and substantially filled with powder, a spring to project the rifle rod from the rear of the axial tube through the muzzle and into the barrel, and means for locking the rod in its projected position and to prevent it from revolving apart from the container, said locking means being releasable by centrifugal force.

3. The combination of a small calibre weapon having a barrel; with a plurality of projectiles, each projectile comprising a body portion, a rifle rod housed within said body portion, a spring which causes said rifle rod to project axially from said body portion into the barrel and a catch which holds said rifle rod in a projected position.

4. The combination of a small calibre weapon having a barrel; with a plurality of projectiles, each projectile comprising a body portion, a hollow rifle rod substantially filled with powder and housed within said body portion, a spring which causes said rifle rod to project from said body portion into the barrel and a catch which holds said rifle rod in a projected position.

5. The combination of a small calibre weapon having a barrel; with a plurality of projectiles, each projectile comprising a body portion, a hollow rifle rod substantially filled with powder and housed within said body portion, a spring which causes said rifle rod to project from said body portion into the barrel, a catch which holds said rifle rod in a projected position and a release for said catch activated by centrifugal force.

JOHN H. PEARSON.
